UNITED STATES PATENT OFFICE.

SILAS EDGAR TROUT, OF PHILADELPHIA, PENNSYLVANIA.

FILING DEVICE.

1,216,017.

Specification of Letters Patent. Patented Feb. 13, 1917.

Application filed August 20, 1913. Serial No. 785,810.

To all whom it may concern:

Be it known that I, SILAS EDGAR TROUT, a citizen of the United States, residing at Philadelphia, in the county of Philadelphia and State of Pennsylvania, have invented 5 certain new and useful Improvements in Filing Devices, of which the following is a specification, reference being had therein to the accompanying drawings.

10 My invention comprises an improved filing device, and while it may be embodied in constructions adapted for various purposes, it is specially designed for use in connection with filing or storing systems of the type 15 employing spacer elements or guide boards arranged in receptacles for containing cost or record cards, correspondence, bills, invoices, documents, or other objects to which access may be desired from time to time.

20 In its broad aspect, the object contemplated is the provision of means whereby any receptacle having sides and a bottom, may be transformed into a filing or storing device.

25 The application to a receptacle of means whereby articles placed therein may be maintained in separated and segregated arrangement; whereby, in the case of cards, documents, correspondence, and the like, the 30 contents will be filed in vertical position, easily accessible and determinable, but prevented from sagging or becoming promiscuously disarranged; and the production of these results by an instrumentality which 35 may be readily attached to and detached from a receptacle, are objects attained by this invention.

In card index, and similar filing and storing systems, considerable confusion and 40 bother resulted when it became necessary to transfer the contents of a filled file to a transfer box for storage. The present invention is designed with the object of eliminating this difficulty.

45 Added to the above objects and advantages, the device comprising my invention as herein described, is simple, practical, economical of manufacture, and easily applied. It makes provision for completely covering 50 the receptacle, thus eliminating dust, and aiding materially in the furtherance of fire proof filing systems.

55 Other objects and advantages will in part be obvious, and in part be made clear in the following description.

In the accompanying drawings made a part hereof there is illustrated an embodiment of the invention, the same serving in conjunction with the description to illustrate its principles, and wherein:

Figure 1 is a view in perspective of a form of the invention applied;

Fig. 2 is a sectional side elevation;

Fig. 3 is a detail view in perspective, partly in section, showing the assemblage of 65 the units;

Fig. 4 is a detail section of a clip member; Fig. 5 is a perspective of a modification; and

Fig. 6 is a sectional view of the same.

As here shown, the invention comprises the following units:—supporting or carrying units; guide or spacer units maintained thereby; a cover unit, and the receptacle or article to which the device is attached. The 75 supporting units comprise guide board or spacer supports in the form of clips, the guide boards being carried thereby. The clips are applicable to the sides of a receptacle, and have a portion formed to receive 80 and retain a cover.

In furtherance of a principle of the invention, it is contemplated to provide an ordinary receptacle of a size and shape designed to be placed within a file box, drawer, or 85 other container for cards, documents, correspondence, or the like. The clips and such spacers as desirable, are applied to this box, so that when filled, it is merely necessary to remove the box, insert the cover and store it 90 as a transfer case. If desired, a separate cover could be placed on the box, the clips and spacers being removed and attached to the box to be inserted in the drawer or the like.

Referring now specifically to the drawings, in which like characters designate like parts in the specification, 1 represents a receptacle, sides 2 of which are preferably intermediately reduced in height as at 3. For 100 the purpose of providing this receptacle with spacer elements or guide boards, and transforming it into a file box, guide board or spacer, carriers 4 are designed.

The carrier members are in the form of 105 clips consisting of an outer portion 5, an inner portion 6, in spaced relation, and adapted to be forced down over and embrace snugly the sides of the receptacle. The upper portions of the clips are formed into 110

grooves or guideways 7 for the reception of a cover 8.

One manner in which these clips may be formed is illustrated in Fig. 4. The outer portion is extended at an angle to the side 5 to form a top portion 9. Here the material which is preferably resilient metal, is bent back upon itself as at 10 to form the inner upper surface of the guideway or cover retainer. It is then carried downwardly as at 11, in alinement with the side 5, from which it is extended outwardly at an angle to form the portion 12. This portion is preferably wider than the top portion 9, for reasons hereafter to be explained, and forms the lower surface of the guideway 7.

The clips or carriers are provided with means for the reception and retention of 20 guide or spacer elements. In the embodiment illustrated in Figs. 1, 2, 3 and 4, slots 13 are shown. They are preferably arranged vertically on the inner surface of the clips, and are of a size and depth adapted to receive and retain snugly lugs or 25 projections 14 carried by guide boards or spacer elements 15.

The clips or carriers are arranged on opposite sides of the receptacle, the slots being 30 preferably in alinement, and of sufficient number to meet various requirements. In practice the slots in the carriers and the lugs on the spacers are of a depth sufficient to retain the spacers in vertical position 35 without the necessity of extra instrumentality secured in the bottom of the box for this purpose. The surface 12 being wider than the surface 9, and the slots being extended therein, permits the lugs to enter into the 40 space between the sides 5 and 6 of the clips or carriers. This arrangement together with the substantial depth of slots and lugs insures the stable vertical retention of the spacers, and prevents their displacement 45 when the contents may be of such a nature as to warp or bulge them.

For application to a receptacle the sides of which are not dished out as in Fig. 3, the embodiment illustrated in Figs. 5 and 6 50 is provided. In this instance, lugs or projections 17 take the place of the slots previously described; and when so constructed the guide boards may be constructed without lugs. Should it be desirable to have an 55 interlocking action between the carriers and the receptacle toothed members 18 driven inward from the metal of the sides of the clips may be provided.

From the foregoing it will be readily seen 60 that my invention applied to a receptacle provides for its subdivision into any desired number of compartments; for the vertical retention of any papers, documents or the like filed therein; and for the exclusion 65 of follower blocks and other instrumentality

placed in the receptacle to insure stability of the spacers and compact retention of the contents.

By applying the carriers and spacers to an ordinary receptacle and placing it in the permanent file box or drawer a combined file and transfer box results. When it has been filled it is only necessary to remove the receptacle and insert the cover. It is then ready for storage, the contents being in their original compartments. By this arrangement the displacement, loss or mutilation 70 which frequently attended the transfer of papers from a file to a place of storage is eliminated, and the contents are maintained 75 in a manner which minimizes their danger of exposure to fire, water, dust, destruction or mutilation.

Should it be desirable, one set of clips 80 may be taken from one receptacle and placed on another. The contents being in separated and segregated arrangement they are easily withdrawn, the spacers being carried with them if necessary. In making a transfer without the removal of the clips, the 85 contents of each separate compartment may be removed, the spacer elements supporting the remaining papers or the like and preventing them from falling or becoming misplaced.

It has been the object of the present invention to provide a filing device which will be simple, practical, economical of manufacture, and which will readily adapt itself to various sizes of filing boxes and various 100 conditions of usage. It will be understood however, that while I have described my invention and illustrated in the embodiment herein shown, I do not wish to limit myself to the precise construction of this disclosure, 105 or to any particular manner in which the same has been or may be carried into effect, as many changes in the construction and arrangement of parts may be made without departing from the main principles of the 110 invention, or sacrificing its chief advantages.

What I claim is:—

1. A filing device comprising spacer-element supports adapted to embrace a portion 115 of the walls of a receptacle; and spacer-elements carried by said supports.
2. A filing device comprising spacer-element supports adapted to be removably mounted on a receptacle; and a cover retaining instrumentality on each of said supports. 120
3. A filing device comprising spacer-element supports adapted to be removably mounted on a receptacle; spacer-elements carried by said supports; and a cover retaining instrumentality on each of said supports. 125
4. A filing device comprising spacer-element supports including clips to be mounted on the sides of a receptacle; and spacer-elements carried by said supports. 130

5. A filing device comprising spacer-element supports including clip members to be mounted on the sides of a receptacle; and a cover retaining instrumentality on each of said supports. 55
6. A filing device comprising spacer-element supports including clip members to be mounted on the sides of a receptacle; spacer-elements carried by said supports; and a cover retaining instrumentality on said supports. 60
7. A filing device comprising spacer-element supports including clip members to be mounted on the sides of a receptacle and means on said clips for carrying spacer-elements; and means on said supports for retaining a cover. 65
8. A filing device comprising oppositely disposed spacer-supports; means carried by a portion of each support for retaining spacer-elements; and means on said supports for retaining a cover. 70
9. A filing device comprising oppositely disposed spacer-supports; adapted to be removably mounted on the sides of a receptacle; means carried by a portion of each support for carrying spacer-elements; spacer-elements maintained in position by said carrying means; means for retaining a cover; and means for impositively locking said spacer-supports to the sides of the receptacle. 75
10. A filing device comprising spacer-supporting clip members adapted to be removably mounted on the sides of a receptacle, said clip members including an inner member and an outer member for engagement with the inner and outer surfaces of the side of a receptacle; means on said clip members for carrying spacer elements; spacers carried thereby; and a cover retaining means on each of said clips. 80
11. In combination with a receptacle, a filing device comprising spacer supporting clip members disposed on opposite sides of the receptacle; means on said clip members for carrying spacers; spacers carried by said means; and a cover retaining instrumentality on each of said supports. 85
12. In combination with a receptacle, a filing device comprising spacer supports including clip members adapted to be removably mounted on the sides of the receptacle and means on each of said clip members for carrying spacers; spacers carried by said means; cover retaining instrumentalities on said supports; and means for impositively locking said clip members to the sides of the receptacle. 90
13. As an article of manufacture, a spacer supporting clip for filing devices comprising receptacle side embracing members; and means on one of said members for carrying spacers. 95
14. As an article of manufacture, a spacer support for filing devices comprising members for embracing the sides of a receptacle; and means thereon for retaining a cover. 100
15. As an article of manufacture, a spacer support for filing devices comprising members for embracing the sides of a receptacle; means thereon for carrying spacers; and means thereon for retaining a cover. 105
16. As an article of manufacture, a spacer support for filing devices comprising two clip members each adapted for embracing a side of a receptacle; the body portions of each being bent to form a cover retaining groove; and means on each of said clip members for carrying spacer elements. 110
17. As an article of manufacture, a spacer supporting element for filing devices comprising a body portion; two oppositely disposed portions in spaced relation connected to said body portion to form a clip; said body portion being bent to form a cover retaining groove; and means on one of said oppositely disposed portions for retaining spacers. 115
18. A filing device comprising members adapted to embrace a portion of the sides of a receptacle; and means thereon for retaining spacers. 120
19. A filing device comprising oppositely disposed members adapted to embrace a portion of a receptacle; and means carried by certain of said members for retaining spacer elements. 125
20. As an article of manufacture for use in a filing device, a receptacle side embracing member; and means thereon for retaining a spacer element. 130
